UNITED STATES PATENT OFFICE.

WILLIAM ALMA BRADLEY, OF SPOKANE, WASHINGTON.

OPERATING MECHANISM FOR ORE-JIGS.

979,253.

Specification of Letters Patent. Patented Dec. 20, 1910.

Application filed December 28, 1909. Serial No. 535,277.

To all whom it may concern:

Be it known that I, WILLIAM A. BRADLEY, a citizen of the United States, and a resident of Spokane, in the county of Spokane and State of Washington, have invented a new and Improved Operating Mechanism for Ore-Jigs, of which the following is a full, clear, and exact description.

My invention relates to ore jigs and more particularly to the gearing used for actuating certain movable parts thereof.

Stated more specifically, my invention comprehends a plurality of rocking shafts provided with tappets and connected together by links and cranks in such manner that the shafts rock in opposite directions, one group of tappets being raised while another group is lowered, the tappets playing upon plunger rods which are connected with the plungers for agitating the ore and the liquids with which the same is mixed.

Reference is to be had to the accompanying drawings forming a part of this specification, in which similar characters of reference indicate corresponding parts in all the figures.

Figure 1 is a view partly in side elevation and partly in section, showing my improved ore jig, and particularly the gearing used for actuating the movable parts thereof; Fig. 2 is a view mainly in elevation but partly upon the section upon the line 2—2 of Fig. 1, looking in the direction of the arrow, and showing the rocking shafts mounted in their respective bearings and properly connected, for the purpose of actuating the plunger rods; and Fig. 3 is a vertical section on the line 3—3 of Fig. 1, looking in the direction of the arrow.

At 4 is a framework and at 5 is a receptacle used for holding the ore and water or other liquid. The receptacle is provided with a cover 6 and extending through the latter are bearing sleeves 7, each provided at its top with an annular flange 7^a, the latter being sunken slightly into the cover 6 so as to afford a good seat for the bearing sleeve. Plunger rods 8 extend vertically through the bearing sleeves and mounted upon the lower ends of the plunger rods is a plunger 9 adapted to slide vertically within the receptacle.

At 10, 11, 12 (see Fig. 1) are supporting beams and mounted upon the latter is a cross beam 13. A base plate 14 is supported upon the cross beam and is provided with

pedestals 15 extending upwardly. These pedestals are provided with bearings 16 and supported by these bearings is a shaft 17 provided with a cranked portion 17^a. That is to say, the shaft 17 is slightly bent so as to form a crank, as will be understood from Fig. 3. A bearing 18 containing a split ring bushing 19 is mounted upon the crank 17^a and supports a stirrup 20, this stirrup being provided at its bottom with an eye 21, and a connecting rod 22 is threaded at its upper end and extends through this eye. Engaging the threaded portion of the connecting rod 22 and disposed upon opposite sides of the eye 21 are two nuts 23, 24 which are used to clamp the connecting rod 22 rigidly in relation to the stirrup 20. The connecting rod 22 extends through an opening 25 in the base plate.

At 26, 27, 28, 29 (see Fig. 2) are bearings, the bearings 27, 28 being cast integrally together for the purpose of securing proper rigidity and also of simplifying the construction. A rocking shaft 29 is journaled in the bearings 26, 27, and an arm 30 provided with a massive annular portion 30^a is mounted rigidly upon the shaft 29, which arm, because it rocks with the shaft 29, I designate as a "rocking arm." The rocking arm 30 carries a crank pin 31 provided with an oil duct 31^a whereby it is lubricated. Mounted rigidly upon the shaft 29 is another rocking arm 32. A link 33 is connected with the lower end of the rocking arm 32 by aid of a pivot pin 34, and for this purpose the link 33 is provided with enlarged end portions 33^a. A pivot pin 35 connects one of these end portions with another rocking arm 36, the latter being mounted upon a rocking shaft 37 disposed adjacent to the rocking shaft 29. A key 38 secures the rocking arm 36 rigidly in its position just described. Tappets 39 are, by aid of collars 40, secured rigidly upon the shaft 37. Similarly tappets 41 are, by aid of collars 42, mounted rigidly upon the shaft 29. The tappets 39 extend in a direction contrary to that in which the tappets 41 extend, all of the tappets, however, being approximately horizontal though capable of a limited vertical rocking movement. The plunger rods 8 are encircled by springs 47, and at their upper ends are provided with hollow cylindrical heads 43, into which are driven wooden pins 43^a adapted to receive the impact of the tappets 41. Similarly the plunger rods 48

are provided with cylindrical heads 49, the structure of which is identical with that of the cylindrical heads 43. The plunger rods 48 are encircled by springs 50. The plunger rods 8 being in alinement with the plunger rods 48, the cylindrical heads 43 are in alinement with the cylindrical heads 49. The plunger rods 48 support a plunger 9^a in all respects similar to the plunger 9. The plungers 9, 9^a are adjustable by aid of nuts 44, 45, and below the nuts 45 are bearings for the upper ends of the springs 47 and 50. Fixed and loose pulleys 51 and 52 are mounted upon the shaft 17 for the purpose of turning the same. Said shaft is also provided with a fly wheel 53.

The operation of my device is as follows: The parts being assembled as above described and ore being fed into the receptacle 6 in the manner heretofore employed, or in any manner desired, and the receptacle being filled with water or other suitable liquid, power is applied to the pulley 51. This turns the shaft 17, and as the cranked portion 17^a is actuated, the connecting rod 22, acting through the rocking arm 30 causes the shaft 29 to rock. This shaft, acting through the rocking arm 32, link 33, and rocking arm 36, causes the other shaft 37 to rock, each of its movements, however, being in a direction opposite that of the corresponding movement of the shaft 29. The tappets 41, 39 are therefore rocked in unison, but in opposite directions. That is to say, as the tappets 41 descend, the tappets 39 ascend, and vice versa. The plungers 9, 9^a are thus each alternately raised and lowered, one plunger rising as the other descends. These plungers acting upon the liquid and ore produce the jiggling action desired. Whenever one of the wooden plugs 43^a becomes worn out, or battered to such

an extent as to be useless, it is pulled out of its cylinder and a new plug substituted. In this way direct wear upon the heads 43, 49 is greatly reduced.

It will be noted that the up stroke of the plungers 9 9^a is not caused directly by the tappets, but rather by the automatic extension of the springs 47, 50. What the tappets do, therefore, is merely to depress the plunger rods 8, 48, as above described. The various rocking arms and the link 33 so connect the shafts 29, 37 together and with adjacent movable parts that each tappet is actuated by positive movements.

Having thus described my invention, I claim as new and desire to secure by Letters Patent:

A device of the character described, comprising a pair of rocking shafts disposed parallel with each other, tappets mounted rigidly upon one of said shafts and extending therefrom in a particular direction, tappets mounted rigidly upon the other shaft extending in a direction opposite the particular direction first mentioned, so that the free ends of said tappets are brought into approximate alinement, means for applying power to one of said rocking shafts, cranks mounted upon the respective rocking shafts and extending therefrom at an angle to the general plane occupied by said tappets, and a pitman connected with each of said cranks for transmitting power across from one crank to another.

In testimony whereof I have signed my name to this specification in the presence of two subscribing witnesses.

WILLIAM ALMA BRADLEY.
